REFRIGERATOR MULLION CONSTRUCTION
FOR PREVENTING CONDENSATION

Willis E. Hursey, Oak Park, and Gilbert Strunk, Glen Ellyn, Ill., assignors to Seeger-Sunbeam Corporation, St. Paul, Minn., a corporation of Minnesota

Application January 9, 1946, Serial No. 639,945

8 Claims. (Cl. 62—89)

1

Our invention relates to an improvement in refrigerator wherein it is desired to provide a means of preventing condensation on the mullion or mullions between adjacent doors.

In refrigerators having a plurality of doors, some difficulty is experienced with condensation on the mullion or frame member between the doors. In many instances this mullion includes an outer metallic covering, an inner metallic lining, and breaker strip means connecting the two liners. If the doors extended flush with the outer surface of the mullion, probably little condensation would be experienced. Actually, however, the doors usually project outwardly from the mullion providing a relatively narrow crevice between adjacent doors. Due to the restricted size of this crevice air does not circulate freely against the mullion and heat is not transmitted from the air to the mullion as readily as to the exterior surfaces of the refrigerator.

It is the object of the present invention to produce a mullion construction which will avoid many of the previous difficulties insofar as the collection of condensation is concerned. In order to prevent condensation on the outer surface of the mullion, we project a part of the outer surface of the mullion outwardly between the doors to a point where the mullion will be at least partly in contact with moving air. As a result heat is transmitted somewhat more readily to the mullion, preventing the outer surface thereof from dropping to a sufficiently low temperature to condense moisture in the air.

It is usual construction to separate the metallic lining of a refrigerator cabinet from the outer metallic covering of the same by means of a suitable breaker strip formed of material having relatively poor heat conductive properties. Thus while a certain amount of heat is conducted into the refrigerator through the breaker strips and the like, the temperature of most portions of the outer covering is prevented from dropping sufficiently to cause condensation because of the ambient air. In confined spaces, however, such as the exposed outer covering of a mullion between adjacent door openings or the like, the air does not circulate freely, allowing the temperature of this portion of the cabinet surface to drop below the temperature of other portions of the outer refrigerator covering. The present invention involves the extension of the mullion surface sufficiently close to the surface of the door to be positioned in the path of circulating air. As a result the temperature of the outer surface of the mullion is maintained at absolutely the

2

same temperature as the remainder of the outer surface of the refrigerator. In some constructions it is necessary that the projecting portion of the mullion extend flush with, or even outwardly of the outer door surface in order to accomplish the desired result.

These and other objects and novel features of our invention will be more clearly and fully set forth in the following specification and claims.

10 In the drawings forming a part of our specification:

Figure 1 is a front elevational view of a refrigerator cabinet showing our new construction.

15 Figure 2 is a perspective view, partly in section, showing the arrangement of the mullion and the doors engaging the same.

Figure 3 is a sectional view through the mullion and the adjoining doors.

20 Figure 4 is a view somewhat similar to Figure 3 showing the projecting portion of the mullion extending at least flush with the outer door surfaces.

The refrigerator A may be of any shape or design and the specific cabinet structure illustrated 25 is merely demonstrative of one form of our invention. The refrigerator cabinet A includes a cabinet body 10 of usual type having doors 11 and 12 secured thereto. Hinges 13 are disclosed supporting the door 11 and oppositely disposed hinges 30 14 are provided for supporting the door 12. Latches 15 and 16 of any suitable type or design are provided for holding the doors in closed position against the refrigerator body 10.

35 Interposed between the doors 11 and 12 we provide a mullion 17 against which the marginal edges of the doors may engage. The mullion 17 is shown as including an inner liner 19 extending from the inner surface of the mullion and a channel shaped outer member 20 forming the outer surface covering element. Insulation 21 40 may be provided within the mullion and if desired this insulation may comprise a structural frame member reinforcing the inner and outer coverings 19 and 20.

45 In the particular form of construction illustrated the inner covering member 19 is formed of metal or other material of relatively high heat conductivity. The outer covering 20 is preferably formed of plastic, rubber, or a rubber substitute. Certain rubber base plastics have been found particularly useful, although virtually any plastic having low heat conductivity may be used to accomplish the desired result.

50 The outer covering 20 is shown as including a central outer covering surface 22, inwardly and

rearwardly tapering wall portions 23 and 24 connected thereto, and parallel wall portions 25 and 26 secured to the tapered wall portions 23 and 24 respectively. This construction provides a channel like arrangement, the open edge of which is closed by the inner covering 39. Integral with or secured to the central outer covering surface 22 we provide an outwardly projecting hollow bead 27. This bead extends outwardly to a point almost flush with the outer coverings 29 and 30 of the doors 11 and 12. The extension of the bead 27 is sufficient to position the outer end of the bead in the path of circulating air so as to maintain the exposed portion of the outer covering 20 at a temperature above the usually experienced condensation point. In any event the exposed portion of the mullion covering 20 is maintained at approximately the temperature of the remainder of the outer covering of the refrigerator.

The doors 11 and 12 are shown as including outer coverings 29 and 30 and inner coverings 31 and 32 respectively. The inner covers 31 are dish shaped in formation having a flat inner surface substantially parallel to the outer surface and having off-set edges. The inner covering 31 includes the substantially flat inner surface 33 and tapered edges 34 which terminate in an outwardly extending flange 35 substantially parallel to the inner covering portion 33. The inner door lining 32 is likewise provided with a substantially flat inner surface 36, tapered marginal edges 37 terminating in a peripheral outwardly extending flange 38.

The outer door coverings 29 and 30 are provided with inturned marginal edges 40 and 41 respectively, terminating in inturned marginal flanges 42 and 43, respectively. The flange 42 of the outer covering 29 is connected in spaced relation to the inner covering 31 by any suitable means such as screws or bolts 44, a breaker strip 45 of material possessing relatively low heat conductivity being anchored between these flanges. The breaker strip 45 is likewise provided with a hollow bead 46 overlying the inner surface of the flange 35 so as to contact the portion of the refrigerator cabinet around the door opening.

The flange 43 of the outer door covering 30 is connected to the flange 39 of the inner door covering 32 by any suitable means such as the bolts or screws 47. A breaker strip 49 is anchored between the flanges 43 and 39. A hollow bead 50 forms a part of the breaker strip and is designed to overlie the inner surface of the flange 39 and to contact the outer surface of the refrigerator.

It is not necessary that the projecting portion 27 of the mullion outer covering be integral with the outer covering, but it is usually convenient to provide such an arrangement, and certain advantages are obtained by making the outer mullion covering 20 in one piece. In actual practice, however, it would also be possible to provide the outer mullion covering in three separate parts as best illustrated in Figure 4 of the drawings. As indicated in Figure 4 the mullion 51 may include an inner covering 52 which may be of material of high heat conductivity and to which are secured a pair of angular breaker strips 53 and 54. The breaker strips 53 include parallel portions 55 and 56 respectively, tapered or inclined surfaces 57 and 59 respectively, and aligned and opposed sections 60 and 61 respectively. The aligned portions 60 and 61

may be connected by projection portion 62 which may be made of material of high conductivity. Marginal flanges 63 and 64 are formed on the projecting portions 62, these flanges overlying the marginal edges of the breaker strip portions 60 and 61 and being connected thereto by any suitable means such as bolts or screws 65.

It will be noted that in the construction illustrated in Figure 4 the projecting portion 62 of the mullion extends outwardly beyond the surface of the doors 11 and 12. The amount of extension of the projecting portion of the mullion is sufficient to place this projecting portion in the path of sufficient circulating air to prevent the formation of condensation thereupon. Where the space between the doors 11 and 12 is relatively narrow the projection of the extension often must be increased. Where the space between adjacent doors is somewhat wider the length of the projection may be usually diminished to some extent.

In accordance with the patent statutes, we have described the principles of construction and operation of our refrigerator, and while we have endeavored to set forth the best embodiment thereof, we desire to have it understood that obvious changes may be made within the scope of the following claims without departing from the spirit of our invention.

We claim:

1. A refrigerator comprising a cabinet body having a pair of door openings in one side thereof, a mullion in said body between said openings, a door in each of said openings, said doors being hinged to sides of said door openings opposite said mullion, marginal portions on said doors overlying portions of said cabinet side and mullion in closed positions of the doors, and a projecting member on said mullion projecting outwardly beyond said one cabinet side between said marginal portions of said doors.

2. A refrigerator comprising a cabinet having a pair of door openings in one side thereof, a mullion between said door openings, an outer cabinet covering, an inner cabinet liner, and a breaker strip between said inner and outer coverings about said door openings, doors in said openings, said doors having marginal portions overlying portions of said outer covering adjacent said door openings, and a projecting member on said mullion projecting outwardly from said one cabinet side between said marginal door portions to transmit heat to said mullion.

3. A refrigerator construction including a cabinet body having a pair of door openings in one side thereof, a mullion in said body between said openings, a door in each of said openings, a marginal edge on each of said doors designed to overlie a portion of said mullion, and a projecting portion on said mullion projecting forwardly from the mullion between said marginal door portions.

4. A refrigerator including a cabinet body having a pair of door openings in one side thereof, a mullion in said body separating said openings, a door in each of said openings, a marginal edge on each of said doors designed to overlie a portion of the outer surface of said mullion, sealing means interposed between said door and the outer surfaces of said mullion, and a projecting member on said mullion extending between said marginal portions of said door.

5. A refrigerator including a refrigerator body having a pair of door openings therein, a mullion in said body between said door openings, doors in

each of said openings, each said door extending partly into the opening and having a peripheral outwardly extending lip overlying the cabinet body and mullion adjacent the door opening, sealing means between said lip and the portion of the cabinet body and mullion over which said lip extends, and a projection on said mullion extending outwardly between said lips.

6. A refrigerator construction including a cabinet having a pair of door openings therein and having a mullion between said openings, doors in each of said openings, a projecting edge on each of said doors designed to overlie a portion of said mullion, an outer covering on said mullion, and a projecting member on said outer covering projecting outwardly between said edges.

7. A refrigerator including a cabinet having a pair of door openings, a mullion separating said openings, said mullion having an outer covering including a central projecting rib and a pair of outwardly extending flanges connected thereto, doors in said openings, a lip on each of said doors overlying an outturned flange of said mullion, said projecting rib extending between said lips.

15

8. A refrigerator including a cabinet having a pair of door openings, a mullion separating said openings, said mullion having an outer covering including a central projecting rib and a pair of outwardly extending flanges connected thereto, doors in said openings, a lip on each of said doors overlying an outturned flange of said mullion, said projecting rib extending between said lips, and sealing means interposed between said lips and said outturned flanges.
